CAN PUNCTURING DEVICE

Ward E. Snowden, Modesto, Calif., assignor to
 Ansul Chemical Company of California, a corporation of California.

Application May 2, 1941, Serial No. 391,557

3 Claims. (Cl. 221—23)

This invention relates in general to a can supporting and puncturing device.

At the present time certain gaseous materials which are used as produce fumigants are distributed to the trade in sealed, relatively small-size cans, and these materials are under relatively high pressures in the cans; one of such materials being methyl bromide. In order to effectively and safely puncture a can of such pressure fluid material and discharge such fluid into a produce chamber to be fumigated, it is necessary to employ a device especially designed for this use.

It is therefore the present object of this invention to provide a unique device to support and puncture a sealed can filled with a pressure fluid, and to immediately thereafter direct the discharge of the pressure fluid contents to a selected point.

A further object of the invention is to provide a can supporting, puncturing, and pressure fluid discharging device which is adapted for one-hand operation; the device including a pistol grip type handle and an operating trigger associated with said handle.

A still further object of the invention is to provide locked but releasable holding means to maintain the can in engagement with the puncturing tube and sealing collar after the can puncturing operation has been accomplished.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 of the drawings is a side elevation of the device with a can supported thereon, and prior to puncturing of the can.

Figure 2 is a similar view partly in section but after puncturing of the can.

Figure 3 is a rear end view of the device.

Referring now more particularly to the characters of reference on the drawings, the device comprises an elongated frame or body 1, preferably of T form in section, having a pistol type grip 2 formed with and depending from one end thereof. The body is slotted vertically at the end adjacent grip 2, as indicated at S, and this slot extends into the upper end portion of the

grip for a short distance. A full length trigger 3 is disposed ahead of grip 2 and projects at its upper end into such slot, where it is pivoted as at 4. An upstanding finger 5 is formed integral with trigger 3 above pivot 4 and projects through the slot to a termination a short distance above the upper edge of body 1.

A circular, locking eccentric 6 is disposed in slot S rearwardly of finger 5 and is mounted on a cross pin 7; a substantial portion of the periphery of such locking eccentric being exposed at the rear end of the device and accessible for rolling movement by the thumb of a person's hand, which engages grip 2. The face of eccentric 6 is of substantial width and is knurled to assure proper frictional engagement with the rear edge of finger 5, and when the eccentric is rolled into engagement with said edge of the finger the center of weight of said eccentric urges the latter in a locking direction. A stop pin 8 projects laterally from one side of the locking eccentric and engages the back of grip 2 alongside the slot when the eccentric is in released position, and assures that it is held in proper position to be rolled into locking engagement with finger 5.

At the end opposite grip 2, body 1 is formed with an upstanding boss 9 through which a can-puncturing tube 10 extends at an upward and outward slope. One end of the can puncturing tube projects rearwardly some distance from boss 9, and is beveled and sharpened to form a diagonal cutting lip 11. A resilient and compressible sealing collar 12, preferably of rubber, surrounds the rearwardly projecting portion of the can puncturing tube, and is initially of substantially the same length as such projecting portion of the tube. At the end opposite cutting lip 11, and at the forward end of boss 9, the tube 10 communicates with a fitting 13 threaded into the boss. A relatively long but small diameter discharge pipe 14 is attached to and projects from such fitting.

Intermediate its ends the body is fitted with upstanding transversely spaced can locating fingers 15 which are of spring metal and formed to engage opposite sides of a can 16 with a symmetrical but easy fit.

In use, a can to be punctured is disposed on its side on body 1 lengthwise thereof and between locating fingers 15; the finger 5 at such time being retracted, the trigger advanced, and the puncturing tube and sealing collar merely abutting the exterior of the end of the can 16. The operator then grasps the grip 2 of the device and

squeezes the trigger toward such grip, which advances finger 5, together with the can 16, toward and into forceful engagement with puncturing tube 10. When this occurs the cutting lip 11 of the puncturing tube pierces through the end of the can. At the same time sealing collar 12 is firmly compressed against the end of the can and forms a complete seal with said end of the can about the tube, preventing leakage. When the can has been punctured, as above, the operator rotates locking eccentric 6 with his thumb until it frictionally engages the back of finger 5; such finger then being held in advanced position, as shown in Fig. 2, preventing the can 16 from backing away from the puncturing tube 10.

When the can has been punctured as above, the pressure fluid contained in the can forcefully vents through puncturing tube 10 and pipe 14; the operator directing such pipe into the produce chamber to be fumigated. It will be seen that the device functions as a fluid discharge pistol or gun, enabling the operator to manipulate the device with one hand and stay well clear of the discharging fluid.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A can supporting and puncturing device comprising an elongated body, a rigid can puncturing tube mounted on the body adjacent one end and projecting toward the other end in spaced relation to said body, a hand grip depending from the body at said other end, a trigger pivoted on a transverse axis relative to the body and depending adjacent said hand grip, an upstanding finger on and projecting upwardly from said trigger, said finger being adapted upon swinging of the trigger toward the hand grip to

move in a direction to engage and advance a can supported on the body between the puncturing tube and said finger, and a movable locking member mounted on the body and arranged to releasably engage said finger when the latter is disposed in can engaging and advanced position.

2. A can supporting and puncturing device, comprising an elongated body including a depending hand grip at its rear end, a trigger disposed adjacent the hand grip, a can puncturing tube mounted on the body adjacent its forward end and projecting rearwardly in vertically spaced relation above the body, the body being slotted therethrough above the trigger, the upper end of the latter projecting into said slot, means pivoting the trigger in the slot, an upstanding finger formed on the trigger and projecting upwardly through the slot to a termination thereabove, said finger being adapted to engage and advance a can supported on the body into puncturing engagement with said tube, and a locking eccentric pivoted in the slot rearwardly of the finger, said eccentric being operative to releasably lock the finger in advanced position.
- 10 3. A can supporting and puncturing device comprising an elongated body, a rigid can puncturing tube mounted on the body adjacent one end and projecting toward the other end in spaced relation to said body, a hand grip depending from the body at said other end, a trigger pivoted on a transverse axis relative to the body and depending adjacent said hand grip, an upstanding finger on and projecting upwardly from said trigger, said finger being adapted upon
- 15 30 35 40 45 swinging of the trigger toward the hand grip to move in a direction to engage and advance a can supported on the body between the puncturing tube and said finger, and a movable locking member mounted on the body and arranged to releasably engage said finger when the latter is disposed in can engaging and advanced position; said locking member comprising a circular eccentric pivoted on a transverse axis, said eccentric being positioned to releasably engage the portion of the finger opposite from the can-engaging portion of the latter.

WARD E. SNOWDEN.
